CLAIM

The ornamental design for a kitchen machine with container, as shown and described.

DESCRIPTION

FIG. 1 is a perspective view of a kitchen machine with container;

FIG. 2 is a left side view;

FIG. 3 is a right side view;

FIG. 4 is a rear elevational view;

FIG. 5 is a front elevational view;

FIG. 6 is a top plan view; and,

FIG. 7 is a bottom plan view.

Portions shown in dashed lines form no part of the claimed design.
